UNITED STATES PATENT OFFICE.

MAUNSELL BOWERS JACKSON, JR., OF TORONTO, ONTARIO, CANADA, ASSIGNOR TO THE
MASTER-VALVE COMPANY, LIMITED, OF TORONTO, ONTARIO, CANADA.

ROTARY VALVE FOR INTERNAL-COMBUSTION MOTORS.

1,410,315.

Specification of Letters Patent. Patented Mar. 21, 1922.

Application filed January 31, 1920. Serial No. 355,520.

To all whom it may concern:

Be it known that I, MAUNSELL BOWERS JACKSON, Junior, a subject of the King of Great Britain, of the city of Toronto, in 5 the county of York, Province of Ontario, Canada, have invented certain new and useful Improvements in Rotary Valves for Internal-Combustion Motors, of which the following is a specification.

10 This invention relates to valves of the rotary tubular type in which the same valve controls both the inlet and exhaust, and my objects are (1) to balance the pressure of the gases in the combustion chamber of the engine against the valve, (2) to utilize the heat 15 of the exhaust gases in the valve to warm the incoming combustible mixture thereby cooling the valve and the exhaust gases, (3) to provide a valve which will not warp when heated, (4) to provide a valve which rotates 20 at one quarter the speed of the crank shaft of the motor; and (5) to construct the valve so that it may be adapted for use with a multicylinder motor by coupling the necessary 25 number of valve sections end to end.

I attain my object by means of the constructions hereinafter described and illustrated in the accompanying drawings in which—

30 Fig. 1 is a longitudinal section through the cylinder head of an internal combustion motor provided with a valve constructed in accordance with my invention;

Fig. 2 a similar view of the tubular valve 35 in a different position;

Fig. 3 a transverse section through parts of two cylinder heads provided with my improved tubular valve;

Fig. 4 an end view of one of the valve 40 sections; and

Fig. 5 a plan view, partly in section, of a cylinder head showing more particularly the method of driving the valve.

In the drawings like numerals of reference indicate corresponding parts in the different figures.

1 is a cylinder head in which is formed the combustion chamber 2. Transversely of the head is formed the bore 3 adapted to 50 receive the tubular valve 4, which is preferably formed in sections, as hereinafter described, when applied to a multicylinder engine. The ports 5 are formed in the cylinder head leading from the combustion cham-

ber to the bore 3, their points of communication with the latter being substantially diametrically opposite, so that the pressure of the gases in the combustion chamber is balanced on opposite sides of the tubular valve.

Owing to the wide separation of the ports 5, I prefer to provide an opening 6 for a spark plug leading into each port, so that the ignition of the combustible mixture may take place simultaneously in each port. The cylinder head is provided with water spaces 7 substantially surrounding the bore 3 and the ports 5. In practice, such spaces will, of course, be suitably connected with a water circulating system.

One or more oil holes 8 will also be provided leading to the bore 3 to permit of the proper lubrication of the tubular valve.

If, as indicated in Fig. 3, my invention is applied to a multi-cylinder engine, the valve is divided into as many sections as there are cylinders, and these sections are detachably coupled in such a manner that each section is rotarily adjustable relative to the others, so that the timing of the inlet and exhaust of each cylinder may be suitably arranged.

For the purpose of coupling the valve sections, I provide the end of each section with a series of holes into which are fitted the dowels 9. When two sections are fitted end to end, these dowels form a rotative connection between the two. At the same time, it is evident that one section may be rotarily adjusted relative to an adjacent section by engaging the dowels with suitable holes in the ends of the two sections, so as to bring the ports of the two sections into suitable angular relationship.

The valve may be driven by means of the driving connections shown particularly in Fig. 5. 10 is a coupling member provided with holes similar to the holes in the ends of the valve sections for the reception of the dowels 9 of the end sections. This coupling member has a stub shaft 11 formed thereon, which is suitably keyed to the hub 12 of the gear wheel 13. The hub of this gear wheel has suitable bearings in the side of the cylinder head, ball bearings 14 being preferably employed as shown. Suitable packing 15 is employed to prevent escape of gases round the shaft 11.

Within the hub of the wheel 13 is located

a coil spring 16, which engages the gear wheel and the end of the stub shaft, and this maintains the coupling 10 in proper engagement with the end of the adjacent section 5 of the valve 4.

The gear wheel 13 may be driven from the crank shaft in any desired manner. For a reason which will hereafter appear, it will be driven at one quarter of the crank shaft 10 speed.

The formation of the tubular valve in sections facilitates greatly the manufacture of the engine and overcomes all the difficulties due to warping which occurs if a one piece 15 tubular valve be employed serving a plurality of cylinders. Each valve section is divided by a partition 17 into an inlet chamber 18 and an exhaust chamber 19. As two inlet ports 20 and two exhaust ports 21 are 20 employed in each section of the valve, the partition 17 is U-shaped as shown particularly in Fig. 3. The inlet ports 20 are preferably located outside the walls of the partition 17 at diametrically opposite points and 25 the exhaust ports 21 between the walls of the partition at diametrically opposite points.

The inlet and exhaust chambers 18 and 19 are suitably connected with the intake and 30 exhaust manifolds of the motor as herein-after described. Assuming then the tubular valve to be driven at one-quarter the crank shaft speed, the inlet ports 20 are in each cycle of any one cylinder brought simultaneously 35 into alignment with the ports 5 in the cylinder head, whereupon the charge of combustible mixture is drawn into the cylinder. After the compression and combustion strokes in the cylinder have taken place, the exhaust ports 21 are simultaneously 40 brought into alignment with the ports 5 and exhaust takes place.

It appears then that at all times the pressures on the tubular valve are balanced, which 45 materially reduces the difficulty of lubrication and reduces the wear on the valve, which has heretofore militated against the general use of tubular valves.

The low speed of the valve relative to the 50 crank shaft speed also helps in reducing the wear and simplifies the problem of lubrication.

To provide for the introduction of the combustible mixture into the inlet chambers 55 18 of the valve, and the exhaust of the products of combustion from the chamber 19, I form in the cylinder heads the inlet passages 22 and the exhaust passages 23, which, in practice, will be suitably connected with 60 the intake and exhaust manifolds (not shown). In a multi-cylinder engine, the passages 22 and 23 between two adjacent cylinders may be common to the two cylinders. At the outside of each end cylinder 65 of a multi-cylinder engine, however, one

passage 22 or 23 serves one cylinder only. Each valve section at each end is provided with a series of openings 24 forming communication between the inlet passage 22 and the inlet chamber 18, or the exhaust passage 70 23 and the exhaust chamber 19 as the case may be. The inlet and exhaust chambers of the valve sections are thus at all times in connection with the inlet and exhaust 75 passages in the cylinder heads, while the inlet and exhaust chambers of the valve sections are alternately brought into communication with the ports 5 of each cylinder head as hereinbefore described.

It will be noted that the cool incoming 80 combustible mixture flows through the tubular valve in contact with the partition 17 so the partition is cooled and the mixture warmed, both desirable results.

I deem it preferable, however, to protect 85 the partition 17 from the hot exhaust gases by securing thereto a shield 25 which is held spaced therefrom and may be made of any metal having a sufficiently high melting point or any tough refractory material. 90

The partition will always be formed of sheet metal welded to the valve, preferably by casting its edges in the metal of the valve. The partition being of thin flexible material will not distort the tubular valve by expansion and being protected by the shield will possess all necessary durability. The serious trouble experienced with cast valves of this type is thus entirely overcome and with a balanced two-ported arrangement. 100

What I claim as my invention is:—

1. In an internal combustion motor provided with a plurality of cylinders, the combination of a plurality of cylinder heads having alined bores for the reception of a 105 tubular valve; a tubular valve rotatable in said bores and adapted to control the introduction of the combustion mixture to the various cylinders and the exit of the exhaust gases, said valve being formed in sections 110 one for each cylinder; and detachable couplings for said sections adapted to permit of a rotary adjustment of the sections relative to one another.

2. In an internal combustion motor provided with a plurality of cylinders, the combination of a plurality of cylinder heads having alined bores for the reception of a tubular valve; a tubular valve rotatable in 115 said bores and adapted to control the introduction of the combustible mixture to the various cylinders and the exit of the exhaust gases, the said valve being formed in sections 120 rotatively adjustable relative to one another; inlet and exhaust passages formed in the cylinder heads leading to said bores, adjoining cylinders having a common passage located between them; partitions in 125 said valve, one for each cylinder, dividing the valve into inlet and exhaust chambers, open- 130

ings in the valve being provided forming communications between the inlet and exhaust chambers of the valve and the inlet and exhaust passages of the cylinder heads.

- 5 3. A tubular valve for an internal combustion motor comprising a hollow cast metal cylinder having inlet and exhaust ports formed in its wall; and a U-shaped sheet metal partition separating the inlet

10 from the exhaust ports, said partition hav-

ing its edges cast into the metal of the wall of the valve.

4. A valve constructed as set forth in claim 3 provided with a protective lining for the exhaust side of the U-shaped partition 15 secured to the partition but spaced therefrom.

Signed at Toronto this 23rd day of January, 1920.

MAUNSELL BOWERS JACKSON, Jr.
